US0D1045174S

(12) **United States Design Patent** (10) **Patent No.:** **US D1,045,174 S**
(45) **Date of Patent:** **** Oct. 1, 2024**

(54) **CRYSTAL SOLAR LIGHT**

(71) Applicant: **E. MISHAN & SONS, INC.**, New York, NY (US)

(72) Inventor: **Steven Mishan**, New York, NY (US)

(73) Assignee: **E. MISHAN & SONS, INC.**, New York, NY (US)

(**) Term: **15 Years**

(21) Appl. No.: **29/932,225**

(22) Filed: **Mar. 12, 2024**

Related U.S. Application Data

(62) Division of application No. 29/883,714, filed on Feb. 2, 2023, now Pat. No. Des. 1,026,298.

(57) **CLAIM**

The ornamental design for a crystal solar light, as shown and described.

DESCRIPTION

FIG. 1 is a top, left, side perspective view of a crystal solar light showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in the drawings illustrate portions of the crystal solar light that form no part of the claimed design.

1 Claim, 6 Drawing Sheets
